ELECTRICALLY OPERATED SWITCH
MECHANISM

Arthur Greenwood Kershaw and Norman Greenwood Kershaw, London, England, assignors, by mesne assignments, to The Union Switch & Signal Company, Swissvale, Pa., a corporation of Pennsylvania

Application July 3, 1937, Serial No. 151,878
In Great Britain August 26, 1936

12 Claims. (Cl. 200—98)

This invention relates to electrically operated switch mechanism of the kind comprising a movable contact-actuating member adapted to be moved from one operative position to another by the action of an operating electro-magnet or electro-magnets and has for its object to provide improved mechanism of this character.

According to the principal feature of the invention the mechanical connection through which the effort exerted by the electro-magnet or electro-magnets is transmitted to the contact-actuating member to effect the movement of this member is so constructed that upon this movement being completed the member is positively locked against movement in the opposite direction, this locking being only released by the reverse operation of the electro-magnet or electro-magnets acting through the mechanical connection above referred to.

20 The locking of the contact-actuating member is preferably arranged to be effected during the final stage of movement of the mechanical connection and by an operative part of this connection actually effecting the movement of the contact-actuating member so as to be effected in a simple and effective manner.

In order that the invention may be readily understood an electrically operated circuit controller embodying the invention will now be described by way of example, with reference to the accompanying drawings in which:

Figure 1 is a plan view and Figure 2 a side elevation view of the circuit controller with the casing cover removed, Figure 3 is a plan view 35 of the operating mechanism in a different position from that in which it is shown in Figures 1 and 2, Figures 4, 5, and 6 are sectional views taken on the lines IV—IV, V—V, and VI—VI respectively, of Figure 2.

40 Referring now to the drawings, the electrically operated circuit controller comprises a contact-carrying member 1 mounted upon a pivoted shaft 2 adapted to be rocked from one to the other of two positions in which the contacts 3 engage with corresponding sets of fixed contacts 4, arranged, as clearly shown in Figure 4, radially around the shaft 2.

45 Mounted upon and secured to one end of the shaft 2 is a rocking arm 5 provided with a driving and locking head 6 having mutually inclined flat faces merging into flat faces parallel to the plane containing the axis of rotation of the shaft 2. A pair of electro-magnets 7, 8 of the solenoid type are arranged side by side adjacent to that 55 end of the shaft 2 carrying the rocking arm 5,

the axes of these solenoids 7, 8 being arranged one on each side of the rocking arm 5 and parallel to the axis of the shaft 2. The solenoids of the electro-magnets are provided with axially movable core plungers 9, 10 respectively, the ends 5 of these plungers being pivotally connected at 11 and 12 respectively to a rocking lever 13 adapted to rotate about a fixed pivot 14 intermediate the plungers. Pivotally mounted operating arms 15, 16 are provided one at each side of the driving and locking head 6, the axes of rotation of the pivots 17 and 18 respectively of these arms being at right angles to that of the shaft 2 and lying in a plane at right angles to the general plane of the head 6. The operating arms 15, 16 project inwards toward the head 6, and are respectively pivotally connected at 19, 20 to the left hand ends of suitable adjustable links 21, 22 the other ends of which are pivotally connected at 23, 24 to opposite ends of the rocking lever 13. It will be observed from the drawings that the pivot pins 19, 20 extend into longitudinally extending slots 19', 20' in the links 21, 22.

20 The free or inner ends of the operating arms 15, 16 are provided with rollers 25, 26 respectively pivotally mounted thereon and adapted to engage with the adjacent faces of the driving head 6 in the following manner.

25 The core plunger 9 of the electro-magnet 7 being in its inner position as a result of the energization of the solenoid of this electro-magnet previously effected, the rocking lever 13 is correspondingly inclined, as shown in Figure 3, so that the pivot 23 at one end of the lever 13 is in its inner position, and the pivot 24 at the other end 30 of the lever is in its outer position.

35 Under these conditions the operating arm 15 will have been moved to a position in which the roller 25 on the arm engages with the corresponding face of the driving head 6, which by 40 this movement has been displaced to its extreme position away from the pivot 17 of the operating arm, and has thus rocked the shaft 2 to a corresponding position.

45 The mechanical connection between the core 9 of the electro-magnet 7 and the driving head 6, constituted by the rocking lever 13 and the operating arm 15, is so arranged that in this position of the parts, as shown in Figure 3, the roller 25 on the operating arm, occupies a position in which 50 its line of contact with the head 6 has moved slightly past the plane of the axes of the pivots 17, 18 of the arms 15, 16, the roller 25 abutting against a suitable stop 27 formed on the head 6. It will thus be seen that the head 6, and conse- 55

quently the rocking shaft 2, cannot be displaced towards the pivot 17, owing to the arm 15 having passed slightly beyond its dead-center position, and the shaft 2 is thus locked, so long as the arm 15 remains in the position in which it is shown in Figure 3.

The other operating arm 16 owing to its mechanical connection at 24 with the other end of the rocking lever 13, has rotated to a position 10 out of engagement with the driving head 6, and 15 inclined at an angle thereto, as clearly shown in Figure 3. When it is desired to set the contact-carrying member 1 into its opposite position, the electro-magnet 8 is energized and the corresponding core plunger 10 is moved to its inner position, thereby effecting a corresponding displacement of the rocking lever 13 to its oppositely inclined position.

During this movement of the rocking lever 13, 20 the operating arm 15 is moved out of engagement with the driving head 6, thereby unlocking the latter, while the arm 16 moves towards the driving head 6, and the roller 26 carried on this arm, engages with the adjacent face of the head 6, the edges of which are slightly bevelled, and 25 moves the head towards the pivot 17. This movement of the head 6 effects through the rocking arm 5 a corresponding movement of the rocking shaft 2 to its new position, and the final stage of 30 movement of the operating arm 16, brings the latter into a position corresponding to that above described with reference to the other operating arm 15, so that the driving head 6 and contact-carrying member 1, are now positively locked in 35 the new position.

The movement of the contact-carrying member 1 to its original position above described, is effected in a similar manner, by the energization of the electro-magnet 7, and it will be understood 40 that continued energization of the electro-magnets 7, 8, is not required after the contact-carrying member 1 has been set into one or other of its operative positions in which it is positively locked until the corresponding electro-magnet for 45 effecting movement to the other position is energized.

As shown in the drawings, except in Figure 3, the parts of the circuit controller are shown in 50 positions intermediate their end positions in which the contacts 3 engage with contacts 4 to the left or to the right (Figure 4). In the intermediate position of the shaft 2, all contacts are broken, and in order to ensure that the shaft 2 shall be brought to this position automatically, 55 in the event of its failing to complete its movement in either direction, a spring 28 (Figures 2 and 5) is secured to the shaft 2 by members 29 and 5) and extends into a recess 30 in a member 31, and extends into a recess 30 in a member 31, secured in the base of the controller.

The invention is evidently not limited to the 60 particular construction and arrangement above described, by way of example, which may be varied in many respects without exceeding the scope of the invention.

Having now particularly described and ascertained the nature of our said invention and in what manner the same is to be performed, we declare that what we claim is:

1. Electrically operated switch mechanism 70 comprising a pivoted contact carrying member rockable between two extreme positions, a rocking arm secured to said member and provided with a driving and locking head, and means including two operating arms pivotally mounted at 75 one end on opposite sides of said head and each

provided at the other end with a roller which cooperates with said head for rocking said member between its two extreme positions.

2. Electrically operated switch mechanism comprising a pivoted contact carrying member rockable between two positions, and means including two rollers secured to pivoted operating arms and cooperating with a driving and locking head mounted on a rocking arm secured to said member for rocking said member between its two 10 positions.

3. Electrically operated switch mechanism comprising a pivoted contact carrying member rockable between two extreme positions, a rocking arm secured to one end of said member and provided with a driving head having mutually inclined flat faces merging into flat faces parallel to the plane containing the axis of rotation of said member, two operating arms one pivoted at each side of the driving and locking head 20 for rotation about axes extending at right angles to the axis of rotation of said member and each lying in a plane extending at right angles to the general plane of said head and having one end projecting toward said head, rollers secured to 25 said arms and cooperating with the flat faces of said head, and means for simultaneously rotating said arms in opposite directions between two extreme positions to rotate said member to one or the other of its extreme positions depending upon the extreme positions to which said arms 30 are rotated.

4. Electrically operated switch mechanism comprising a pivoted contact carrying member rockable between two extreme positions, a rocking arm secured to one end of said member and provided with a driving head having mutually inclined flat faces merging into flat faces parallel to the plane containing the axis of rotation of said member, two operating arms one pivoted 40 at each side of the driving and locking head for rotation about axes extending at right angles to the axis of rotation of said member and each lying in a plane extending at right angles to the general plane of said head and having one end projecting toward said head, rollers secured to 45 said arms and cooperating with the flat faces of said head, and means for simultaneously rotating said arms in opposite directions to the relative positions in which the one roller is out of 50 engagement with said head and the other roller is engaging said head at a line of contact which is slightly past the plane of the axes of the pivots of said arms or to the relative positions in which said other roller is out of engagement with said head and said one roller is engaging said head at a line of contact which is slightly past the 55 plane of the axes of the pivots of said arms.

5. Electrically operated switch mechanism comprising a pivoted contact carrying member rockable between two extreme positions, a rocking arm secured to one end of said member and provided with a driving and locking head having mutually inclined flat faces merging into flat faces parallel to the plane containing the axis of rotation of said member, two operating arms one pivoted at each side of the driving and locking head for rotation about axes extending at right angles to the axis of rotation of said member and each lying in a plane extending at right angles to the general plane of said head and having one end projecting toward said head, rollers secured to 60 said arms and cooperating with the flat faces of said head, means for simultaneously rotating said arms in opposite directions to the 65

70

75

- relative positions in which the one roller is out of engagement with said head and the other roller is engaging said head at a line of contact which is slightly past the plane of the axes of the pivots of said arms or to the relative positions in which said other roller is out of engagement with said head and said one roller is engaging said head at a line of contact which is slightly past the plane of the axes of the pivots of said arms, and a stop secured to said head in a position to engage said one or said other roller when such roller is rotated to the position in which its line of contact with said head is past the plane of the axes of the pivots of said arms.
6. Electrically operated switch mechanism comprising a pivoted contact carrying member rockable between two extreme positions, a rocking arm secured to said member and provided with a driving and locking head, and means including two operating arms pivotally mounted at one end on opposite sides of said head and each provided at the other end with a roller which cooperates with said head for rocking said member between its two extreme positions and for locking said member in whichever extreme position to which it is moved.
7. Electrically operated switch mechanism comprising a pivoted contact carrying member rockable between two extreme positions, a rocking arm secured to said member and provided with a driving and locking head, means including two operating arms pivotally mounted at one end on opposite sides of said head and each provided at the other end with a roller which cooperates with said head, and means for simultaneously rotating said operating arms in opposite directions between two extreme positions to rotate said member to one or the other of its two extreme positions.
8. Electrically operated switch mechanism comprising a pivoted contact carrying member rockable between two extreme positions, a rocking arm secured to said member and provided with a driving and locking head, two operating arms pivotally mounted on opposite sides of said head and each extending toward said head and provided at the end nearest said head with a roller which cooperates with said head to rotate said member to one or the other of its extreme positions, and means including a solenoid for operating said arms.
9. Electrically operated switch mechanism comprising a pivoted contact carrying member rockable between two extreme positions, a rocking arm secured to said member and provided with a driving and locking head, two operating arms pivotally mounted on opposite sides of said head and each extending toward said head and provided at the end nearest said head with a roller which cooperates with said head, means including a first solenoid for simultaneously rotating said arms in opposite directions to one relative position to cause the roller on the one operating arm to engage said head and rotate said member to one extreme position, and means including a second solenoid for simultaneously rotating said arms in opposite directions to another relative position to cause the roller on the other operating arm to engage said head and rotate said member to its other extreme position.
10. Electrically operated switch mechanism comprising a pivoted contact carrying member movable between an intermediate position in which all the contacts carried thereby are open and one or the other of two extreme positions and biased to its intermediate position, a rocking arm secured to said member and provided with a driving and locking head, and means including two operating arms pivotally mounted at one end on opposite sides of said head and each provided at the other end with a roller which cooperates with said head for rocking said member between its two extreme positions.
11. Electrically operated switch mechanism comprising a pivoted contact carrying member rockable between two extreme positions, a rocking arm secured to one end of said member and provided with a driving head having mutually inclined flat faces merging into flat faces parallel to the plane containing the axis of rotation of said member, two solenoids provided with plungers and arranged side by side adjacent to that end of said member to which said rocking arm is secured, a rocking lever pivoted intermediate said solenoids and pivotally connected on opposite sides of its pivotal axis with said plungers, two operating arms one pivoted at each side of said head for rotation about axes extending at right angles to the axis of rotation of said member and each lying in a plane extending at right angles to the general plane of said head and having one end projecting toward said head, rollers secured to said arms and cooperating with the flat faces of said head, and links pivotally connecting said rocking lever with said two operating arms respectively.
12. Electrically operated switch mechanism comprising a pivoted contact carrying member rockable between two extreme positions, a rocking arm secured to one end of said member and provided with a driving head having mutually inclined flat faces merging into flat faces parallel to the plane containing the axis of rotation of said member, two solenoids provided with plungers and arranged side by side adjacent to that end of said member to which said rocking arm is secured, a rocking lever pivoted intermediate said solenoids and pivotally connected on opposite sides of its pivotal axis with said plungers, two operating arms one pivoted at each side of said head for rotation about axes extending at right angles to the axis of rotation of said member and each lying in a plane extending at right angles to the general plane of said head and having one end projecting toward said head, rollers secured to said arms and cooperating with the flat faces of said head, and slotted links pivotally connecting said rocking lever with said two operating arms respectively.
